(Cl. D81—1)

Fig. 1

Fig. 2

Figure 1 is a perspective view of an electric toaster embodying my new design;

Figure 2 is a side elevational view of the same;

Figure 3 is a top plan view of the same; and

Figures 4 and 5 are end elevational views of the same taken respectively, from the right and the left of Figure 2.

The undisclosed side is substantially the same as that shown in Figure 2.

I claim:

The ornamental design of an electric toaster, substantially as shown and described.
